WINDOW CHANNEL

Charles P. Schlegel, Rochester, N. Y., assignor to
The Schlegel Manufacturing Company, Rochester, N. Y., a Corporation of New York

Application March 5, 1932. Serial No. 596,946

3 Claims. (Cl. 296—44.5)

The present invention relates to window channels and particularly to those adapted to support the sliding glass window of an automobile, although the invention is applicable to other types 5 of windows.

One object of the invention is the provision of a channel of the class described comprising a substantially rigid channel member which may be readily flexed, without substantially altering its channel shape, so as to fit window openings of 10 different curvatures.

Another object is the provision of such a channel member of metal or other substantially rigid material so formed as to facilitate bending to 15 curved shape to fit different curvatures.

Still another object is the provision of such a channel which is pleasing in appearance, simple in construction, and effective in use.

To these and other ends the invention resides 20 in certain improvements and combinations of parts, all as will be hereinafter more fully described, the novel features being pointed out in the claims at the end of the specification.

In the drawing:

25 Fig. 1 is a fragmentary view of an automobile body equipped with a channel member constructed in accordance with the present invention;

Fig. 2 is a fragmentary vertical sectional view through one of the window frames illustrated in 30 Fig. 1, on a larger scale, showing the relation of the channel member thereto;

Fig. 3 is a bottom view of a window channel constructed in accordance with one embodiment of the invention;

35 Fig. 4 is a perspective view of the channel illustrated in Fig. 3, on a larger scale, the lining material being removed to show more clearly the channel construction;

Fig. 5 is a side elevation view of another modification;

40 Fig. 6 is a bottom view of the channel illustrated in Fig. 5;

Fig. 7 is a vertical sectional view taken transversely of the channel illustrated in Figs. 5 and 45 6 substantially on the line 7—7 of Fig. 6, and

Fig. 8 is a perspective view of still another modification, the channel lining being removed to show more clearly the channel construction.

The same reference numerals throughout the 50 several views indicate the same parts.

The present invention is embodied, in the present instance by way of illustration, in a channel member of substantially rigid sheet material, such, for example, as sheet metal formed 55 with a plurality of hinged sections on certain of the walls thereof, which sections permit the channel member to be bent to curved shape to fit window frames of different curvatures.

Referring now to the drawing, Figs. 5 to 7 60 show a channel member of sheet metal formed

to provide a bottom 11 and side walls 12. The free edges of the side walls are bent outwardly and then rearwardly to form flanges 13 spaced from the side walls 12, as clearly illustrated in Fig. 7. A cushioning lining, preferably in the form of a strip of textile fabric, is arranged on the inner faces of the bottom and side walls of the channel, and is provided with spaced pile surfaces 15 and 16 adapted to engage the faces and side edge, respectively, of a sliding window sash, not shown, to provide a resilient support therefor. The pile surfaces are separated by breaks 17, free from pile, which permit the strip to be bent into channel form. The strip is also provided with breaks 18 on the free edges thereof which extend outwardly and rearwardly over the outer faces of the flanges 13 and thence inwardly and forwardly between the flanges and the outer faces of the side walls 12, being clamped in position against the walls 12 by the flanges 13.

In many of the later designs of automobiles, the top edge of the sliding window sash is arched, and when in the closed position is received in a similarly shaped channel member secured to the top of the window frame. The radii of curvature 85 of these arches are different in different makes of cars, and may, in fact, be different for the various windows of the same car. Due to the difficulty of bending a metal channel member by hand, the arched channels are usually drawn 90 or otherwise formed by the channel manufacturer to fit an arch of a specific curvature, thus placing the channel manufacturer under a great deal of expense in an endeavor to meet the multiplicity of requirements of the automobile industry. As no one form of channel can be made 95 on a large scale, the unit cost of such channels is necessarily increased.

To overcome these objectionable features, the present invention provides a new and more satisfactory channel construction, of the class described, which may not only be standardized and thus produced in large quantities at a reduced cost, but which is adapted to fit any arch between a reasonable maximum radius of curvature and a straight line. To provide this desirable feature, the metal channel is formed with a plurality of slots which extend transversely of and which divide the channel member into a plurality of substantially independent channel 110 shaped portions. The slots do not, however, completely sever the channel member, but are preferably terminated at suitable points to provide thin flexible webs which hingedly connect the portions, and which permit them to be moved 115 relative to each other to provide a flexible channel member adapted to be mounted on window frames of different curvatures. The cushioning lining preferably extends the full length of the channel member and provides a smooth con- 120

tinuous surface in engagement with the sash, the lining being sufficiently flexible to permit the channel to be readily bent into arched form.

Referring again to Figs. 5 and 7, the side walls 12 are provided with pairs of oppositely disposed slots 20 which extend the full height of the side walls and preferably part way across the bottom 11. The slots on one side of the channel member are in the planes of and co-10 operate with the complementary slots on the opposite side of the channel to form pairs of slots which divide the channel into substantially independent channel-shaped portions 21, as clearly illustrated in Figs. 5 and 6. The ends of 15 the slots extend inwardly a short distance across the bottom 11, and are terminated short of each other to provide thin flexible webs 22 therebetween which connect the portions 21. These webs provide hinged connections on the back 20 of the channel member between the portions, and permit the latter to be moved relative to each other to vary the curvature of the channel member. The cushioning lining extends the full 25 length of the channel, and, due to its elastic character, provides a smooth continuous surface at all degrees of curvature of the channel member.

By means of this arrangement, the channel 30 may be standardized and is adapted to be used on either a flat or arched window frame. If the channel is to be mounted on a straight or flat surface, it is secured thereto in the same manner as the usual form of metal channel. When, however, the channel is to be mounted on a 35 curved or arched window frame, each web 22 is bent so that the portions 21 may be moved relative to each other to conform to the curvature of the frame, the amount of bending depending on the degree of curvature.

40 Fig. 8 shows another form of channel construction having a bottom 11a and side walls 12a, the free edges of which are bent outwardly to form flanges 13a arranged to receive and hold a cushioning lining of the type illustrated in Fig. 7, and heretofore described. In this embodiment, the channel member is provided with slots 20a which preferably extend across the bottom 11a for the full width thereof, and substantially the 45 full height of the sides 12a to subdivide the channel into substantially independent channel-shaped portions 21a, as clearly illustrated in Fig. 8. The slots are preferably terminated short of the free edges of the sides 12a to provide flexible members or webs 22a which 50 connect the portions 21a along the free edges of the channel. The webs provide flexible hinged sections or joints on the side walls of the channel member, and permit the portions to be moved relative to each other to vary the degree of 55 curvature of the channel member.

60 In the modification shown in Figs. 3 and 4, the channel member is similar to those above described and is formed to provide a bottom 11b, and side walls 12b the free edges of which are rolled outwardly and rearwardly to form flanges 13b arranged to receive and hold the free edges of a cushioning lining of the type illustrated in Fig. 7. To enable this channel member to be readily bent or flexed, the sides 12b of the channel 65 are provided with pairs of oppositely disposed slots 20b. These slots have portions thereof which extend upwardly along the sides 12b and preferably terminate short of the free edges

thereof to provide flexible webs or connecting sections 22b similar to the web 22a, Fig. 8, while other portions of the slots extend inwardly a short distance across the bottom 11b, and are terminated short of the ends of the complementary slots to provide flexible webs 22c therebetween, similar to the webs 22, Figs. 5 to 7. In addition to the slots 20b, the channel is also provided with a plurality of slots 20c disposed on the bottom 11b intermediate the planes of the slots 20b, as best shown in Fig. 3. The slots 20c extend substantially the full width of the bottom 11b and have the ends thereof substantially in the planes of the ends of the slots 20b, as clearly illustrated in Figs. 3 and 4. By means 80 of this arrangement of slots, the channel is not divided into substantially independent portions, such as shown in Figs. 5 to 8, thus providing a more rigid channel construction. The slots 20b and 20c, however, provide means for weakening the channel so that the latter may be flexed to fit window openings of different curvatures, the webs 22b and 22c acting as hinge sections 85 to facilitate such flexing.

90 It is apparent from the above description that 100 the present invention provides a simple, inexpensive channel construction of pleasing appearance, which is adapted to be readily and easily bent or flexed without buckling or kinking to fit window frames of different curvatures.

95 While certain embodiments of the invention 105 have been disclosed, it is to be understood that the inventive idea may be carried out in a number of ways. This application is therefore not to be limited to the precise details described, but is intended to cover all variations and modifications thereof falling within the spirit of the invention or the scope of the appended claims.

I claim:

1. A window channel comprising a channel 115 member of substantially rigid sheet material having a bottom and side walls, said bottom having a plurality of transverse slots, said sides having transverse slots intermediate the planes of the slots on said bottom, said slots providing a means 120 for weakening said member to permit the latter to be flexed to vary the curvature thereof, and a cushioning lining for said member.

2. A window channel comprising a channel 125 member of substantially rigid sheet material having a bottom and side walls, said bottom having a plurality of transverse slots extending substantially the full width thereof, said sides having pairs of oppositely disposed slots intermediate the planes of said first mentioned slots, each of 130 the slots on said side walls having a part extending substantially the full height of the side wall and terminating short of the free edge thereof, and another part extending inwardly across said bottom, said slots facilitating the flexing of said 135 member to vary the curvature thereof, and a cushioning lining for said member.

3. A window channel comprising a channel 140 member of substantially rigid sheet material having a bottom and side walls, said bottom having a plurality of transverse slots extending substantially the full width thereof, and said side walls having pairs of oppositely disposed slots intermediate the planes of the first mentioned slots, said slots providing means for weakening said 145 member to facilitate the flexing thereof to fit window openings of different curvatures.

CHARLES P. SCHLEGEL.
